Inventor:
Willard A. Larson

UNITED STATES PATENT OFFICE

132,594

DESIGN FOR A BUILDING BLOCK

Willard A. Larson, Preston, Idaho

Application April 10, 1942, Serial No. 106,524

Term of patent 14 years

To all whom it may concern:

Be it known that I, Willard A. Larson, a citizen of the United States, residing at Preston, in the county of Franklin and State of Idaho, have invented a new, original, and ornamental Design for Building Blocks, of which the following is a specification, reference being had to the accompanying drawing, forming part thereof.

Figures 1 and 2 are perspective views showing the two sides and two ends of the block illustrating my design.

I claim:

The ornamental design for a building block, as shown.

WILLARD A. LARSON.
